UNITED STATES PATENT OFFICE.

GEORGE W. COPE, OF DETROIT, MICHIGAN.

DESIGN FOR A HEATING-STOVE.

SPECIFICATION forming part of Design No. 25,007, dated December 24, 1895.

Application filed May 18, 1895. Serial No. 549,839. Term of patent 7 years.

To all whom it may concern:

Be it known that I, GEORGE W. COPE, of Detroit, in the county of Wayne and State of Michigan, have invented a new and useful 5 Design for Heating-Stoves, of which the following is a specification.

My invention consists in a design for heating-stoves hereinafter fully described and claimed.

Figure 1 is a side elevation showing my design for a heating-stove. Fig. 2 is a front end elevation of the same, and Fig. 3 is a top plan view.

A represents a section somewhat like a radiator-loop, but open on one side, and having on the other side an opening for a swinging door, an ash-pit G, and a damper F, and provided with legs E.

D D represent sections somewhat like radi-

ator-loops, but open on both sides. B represents a similar section open on one side and closed on the other, and having a stovepipe-opening C and legs E. The sections are so arranged as to be secured together by rods or bolts, and are ornamented at the top and bottom, as shown in Fig. 1. The front may also be ornamented, as shown in Fig. 2, and the rear of section B may be ornamented or not, as desired.

What I claim as my invention, and desire 30 to secure by Letters Patent, is—

The design for a stove, substantially as herein shown and described.

GEORGE W. COPE.
